UNITED STATES PATENT OFFICE.

FRANK M. PARADISE, OF QUAKERTOWN, PENNSYLVANIA, ASSIGNOR TO MCADOO & ALLEN WELTING COMPANY, OF QUAKERTOWN, PENNSYLVANIA, A COPARTNERSHIP COMPOSED OF HENRY M. MCADOO AND GEORGE H. ALLEN.

GOODYEAR WELT.

Application filed January 26, 1928. Serial No. 249,572.

Objects of the present invention are to provide for thickening the outer edge of the welt and consequently of the sole of the finished shoe; to effect an economy in the use 5 of hides for the manufacture of welts; and to provide a tight inseam in the finished shoe.

To these and other ends hereinafter set forth the invention, generally stated, comprises a Goodyear welt slashed opposite the 10 stitch grooved edge thereof and having a ribbon or strip inserted in the slash.

The invention also comprises the improvements to be presently described and finally claimed.

15 Referring to the drawing

Figure 1 is a transverse sectional view of a shoe showing a welt embodying features of the invention in application thereto.

Fig. 2 is a perspective view of a part of a 20 welt slashed opposite the stitch grooved edge.

Fig. 3 is a similar view showing the slash in open position, and

Fig. 4 is a similar view of a ribbon split 25 adapted for insertion into the slashed edge.

In the drawing 1 is a Goodyear welt slashed

as at 2 opposite the stitch grooved edge 3 and having one or more ribbon insertions 4 arranged and secured in the slash. The outer sole and the stitches are indicated in dotted lines. The ribbon or strip is or may be of 30 any appropriate material, for example leather material, which at present may be regarded as waste, and it may be used in one or more thicknesses and it is secured by a suitable adhesive in the slash 2.

The welt of the invention may be made of 35 comparatively thin and therefore comparatively inexpensive leather while at the same time there is presented a comparatively thick edge. Again the flaring thickness of the 40 welt causes its thinner edge to provide a tight inseam.

I claim:

A Goodyear welt slashed opposite the stitch grooved edge thereof and having a ribbon 45 insertion arranged in the slash and extending flush with the slashed edge to thicken the same, substantially as described.

FRANK M. PARADISE.
